UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

MECHANISM FOR HANDLING FASTENINGS.

Application filed July 15, 1918, Serial No. 244,877. Renewed November 3, 1923.

To all whom it may concern:

Be it known that I, CHARLES C. BLAKE, a citizen of the United States, residing at Brookline, in the county of Norfolk and 5 State of Massachusetts, have invented certain Improvements in Mechanism for Handling Fastenings, of which the following description, in connection with the accompanying drawings, is a specification, like 10 reference characters on the drawings indicating like parts in the several figures.

This invention relates to mechanisms for handling fastenings and similar articles to select or arrange them in a predetermined 15 manner. The invention will be herein disclosed as embodied in a mechanism for arranging tacks, nails and the like for delivery to a fastening inserting mechanism. It is the general object of the invention to devise 20 a mechanism of the character indicated which will be simple in construction, reliable in operation, will require a minimum of attention and can be economically manufactured.

25 To the accomplishment of these objects the invention involves certain novel combination and arrangement of parts and details of construction, the nature of which will be readily understood from the following description of one embodiment of the invention and the novel features of which will be particularly pointed out in the appended claims.

In the accompanying drawings

35 Figure 1 is a front elevation, partly in cross section, of a mechanism embodying the invention in the form at present preferred;

Fig. 2 is a vertical cross sectional view of 40 the mechanism shown in Fig. 1;

Fig. 3 is a plan view of the mechanism shown in Figs. 1 and 2, the casing being shown in cross section in order better to illustrate the enclosed parts; and

45 Fig. 4 is a plan view showing the manner in which the end of the picker is distended at certain times.

The mechanism shown comprises a tack pot or hopper 2 adapted to contain a quantity of tacks, nails or other fastenings. This hopper consists of an upper stationary member *a* and a lower member *b* that is rotatable in a horizontal plane. The part *b* rests on

a collar 3 and is provided with dowel pins 4 and 5, respectively, that project into suitable holes in the upper face of the collar and which compel the lower part *b* of the hopper to rotate with the collar. The collar is driven by a worm gear 6 fast on a short vertical shaft 7 that rotates in bearings 8 formed in the machine frame. A rod 9 projects centrally through the shaft 7 and carries a key 10 at its upper end which fits into a recess in the lower face of the collar 3 and thus forms a driving connection between the worm gear 6 and the collar. 55 A worm 12 mounted on the driving shaft 13 of the mechanism meshes with the worm gear 6 and drives it, the shaft 13 being provided with a pulley 14 which may be belted 60 to any convenient source of power. 65

The upper part *a* of the hopper 2 merely rests on the lower part *b* and it is centered with reference to the latter part by a cover or cap 15 that is bolted to the frame of the 70 machine, this cover being provided with an aperture 16 through which tacks or other fastenings may be thrown into the hopper 2. A stationary raceway 17 leads through an aperture provided in the upper part *a* of the 75 hopper and is supported by a bracket 18 bolted to the machine frame. The raceway leads the fastenings to the point at which it is desired to deliver them and a mechanism is provided to pick up the fastenings from 80 the tumbled mass in the hopper 2 and deliver them to the raceway 17. This mechanism comprises two pickers 20 both mounted to rotate in a vertical plane and arranged to swing alternately through the body of 85 fastenings in the hopper. Each picker consists of an arm curved forwardly in the direction of its rotative movement, as best shown in Fig. 2, and slotted throughout its entire length and width except at a small 90 portion of its shank. The pickers are connected to a shaft 21 supported horizontally in bearings formed integrally with the cover 15 and it is rotated by a belt connection with the main driving shaft 13. In order to support the pickers the shaft 21 has fixed to it 95 a collar 23 to which is bolted an elongated plate 24 that extends at opposite sides of the shaft in the general direction of the length of the pickers. The pickers are secured to 100 the opposite ends of this plate 24 by bolts

105

25 extending through the unslotted portions of the pickers and the pickers are spaced from the plate 24 by collars, one of which is indicated at 26, Fig. 1, that encircle the 5 bolts 25.

It will now be evident that as each picker 20 swings through the mass of tacks in the hopper 2 the shanks or points of certain of the tacks will enter the space between 10 the rails of the picker and the heads of the tacks will rest on the forward edges of these rails. As the picker rises it will lift the tacks so engaged out of the body of tacks in the hopper and the tacks so picked 15 up will slide downwardly under the influence of gravity from the point or end portion of the picker toward the shank of the picker. These tacks, however, are prevented from sliding off the shanks of the 20 pickers by a central stationary member 27, which, as shown in Fig. 2, has a periphery that is circular except at its upper side and the shank of each picker engages this circular peripheral portion during the greater 25 part of its rotative movement. The edge of the upper part of this member 27 is cut off or flattened, as indicated at 28, Fig. 2, and is shaped to form one rail of a short raceway 29, the other rail of this raceway being secured to the part 27 by screws. The member 27 is secured to the cap 15 by screws 32, Fig. 3.

When the forward tack supporting surface of one of the pickers 20 comes into 35 alinement with the upper end of the surface 28 the tacks resting on the shank portion of the picker slide on to it and run down the raceway 29 on to the raceway 17. A short gap 30 is provided between the 40 lower end of the raceway 29 and the upper end of the raceway 17 so that in case the raceway 17 is full the tacks will drop through the space 30 and fall back into the hopper 2. If, however, the raceway 17 is 45 not full the tacks will merely jump the gap 30 and slide down the raceway 17. This action continues as long as the pickers are rotated and the hopper is supplied with tacks, the end portion of each picker lifting 50 a few tacks as it swings upwardly on each rotative movement and these tacks sliding down on to the shank of the picker toward its axis of rotation and then jumping off the picker on to the raceway 28 when the 55 tack supporting surface of the picker comes into alinement with the surface of the raceway. The number of tacks lifted by each picker during a single rotation is relatively small but obviously a sufficient number of 60 pickers can be used to supply tacks to the raceway faster than they are required by the machine or apparatus to which the tacks are delivered by the raceway 17.

After the pickers have passed their 65 delivery point, that is the point at which the

fastenings slide off the shank of the picker on to the raceway 28, it is desirable to clear each picker of any tacks that may still be resting on it. This is particularly true in case a defective fastening has become stuck 70 between the rails of the picker. In order to effect this result a short wedge 31 is fastened into the top of the cover 15 which surrounds the pickers and this wedge is located in a position to enter between the rails of 75 each picker and spread these rails apart at a time when the forward or tack supporting surface of the picker is on the lower side of the picker arm. This spreading of the rails at this particular point in the rotation of 80 the picker forces the rails so far apart that any fastenings that have become wedged between them will be released and will drop back into the hopper. As soon as the picker has passed out of contact with the wedge 85 31 the rails will return again to their normal positions, due to their own resiliency, in readiness to perform their tack picking operation when the picker is again moved 90 through the body of tacks in the hopper.

It will readily be understood that the rotation of the lower part *b* of the hopper greatly facilitates the tack picking operation since it causes a substantially continuous movement of the fastenings into the path of movement of the picker and thus enables the picker to perform its function of taking fastenings from the hopper and delivering them to the raceway until the 100 supply of fastenings in the hopper has become substantially exhausted. It will also be seen that the mechanism is very simple in construction, requires practically no attention on the part of the operative other than to keep the hopper supplied with fastenings and that it can be very economically manufactured.

While I have herein shown and described the best embodiment of the invention of which I am at present aware, it will readily be understood by those skilled in this art that this embodiment may be varied in the arrangement of parts and in the details of construction without departing from the spirit or scope of this invention. It will also be evident that certain features of the invention are applicable to an apparatus designed to handle different types of fastenings than the tacks and nails for which the apparatus shown is particularly designed, or to handle other articles having characteristics which enable them to be handled, arranged or manipulated in the same general manner that fastenings are handled and arranged. Consequently the term "fastenings" as herein employed is used, where the context permits, in a generic sense to designate articles capable of being handled and arranged in the same 115 general manner as fastenings.

What is claimed as new, is:

1. A mechanism for handling fastenings, having, in combination, a hopper constructed to hold a body of fastenings, a picker movable through said body of fastenings and comprising a pair of spaced rails, and means for spreading said rails apart at a predetermined point in the movement of said picker.
- 10 2. A mechanism for handling fastenings, having, in combination, a hopper constructed to hold a body of fastenings, a picker movable through said body of fastenings and comprising a pair of spaced rails, a raceway to which said picker delivers fastenings at a certain point in its movement, and means for spreading said rails apart after the picker has passed its delivery point.
- 15 3. A mechanism for handling fastenings, having, in combination, a hopper constructed to hold a body of fastenings, a picker comprising a pair of spaced rails arranged to support a string of fastenings, operating means for said picker arranged to move the free end of the picker through said body of fastenings, and means con-
structed and positioned to enter between said rails at said free end of the picker at a predetermined point in its operative movement to spread said rails apart.
- 20 4. A mechanism for handling headed fastenings, comprising, in combination, a hopper for holding a supply of said fastenings, a rotatable picker comprising a pair of spaced rails, said picker having an end portion movable through said body of fastenings to pick up fastenings therefrom and having another portion along which the fastenings so picked up slide in a direction away from said end and toward the axis of rotation of the picker, a raceway having a part about which said picker rotates and on to which the fastenings carried by the picker slide under the influence of gravity, and means for spreading the rails of said picker at a point in each rotation thereof after it has delivered its fastenings to said raceway and before it enters said body of fastenings again.

In testimony whereof I have signed my name to this specification.

CHARLES C. BLAKE.
